UNITED STATES PATENT OFFICE.

MORRIS N. DRUCKER, OF CINCINNATI, OHIO.

DESIGN FOR A TRUNK-CLAMP.

SPECIFICATION forming part of Design No. 33,744, dated December 18, 1900.

Application filed November 21, 1900. Serial No. 37,294. Term of patent 7 years.

To all whom it may concern:

Be it known that I, MORRIS N. DRUCKER, a citizen of the United States of America, and a resident of Cincinnati, in the county of 5 Hamilton and State of Ohio, have invented and produced a certain new and original Design for Trunk-Clamps, of which the following is a specification.

Figure 1 is a top view of a trunk-clamp embodying my invention. Fig. 2 is a side elevation of the same. Fig. 3 is an edge elevation thereof.

The principal features of my design are the top and bottom rearwardly-projecting flanges 10 of the side plates. These flanges a a' and a^2 a^3 , projecting rearwardly from the sides A A'

and at substantially a right angle thereto, are of the same length as said sides and have at their ends outwardly-projecting perforated lugs a^4 . At the meeting-line of the sides A A' 20 is an oval elevation a^5 , and upon each side of it, in relief upon the sides A A', are a number of overlapping conventional leaves gradually diminishing in size, so that their outlines form a parabola a^6 . 25

What I claim is—

The design for a trunk-clamp as herein shown and described.

MORRIS N. DRUCKER.
